UNITED STATES PATENT OFFICE.

JOHN M. STUART, OF BOSTON, MASSACHUSETTS.

ANNUNCIATOR-DROP.

SPECIFICATION forming part of Letters Patent No. 402,043, dated April 23, 1889.

Application filed May 22, 1888. Serial No. 274,673. (No model.)

To all whom it may concern:

Be it known that I, JOHN M. STUART, of Boston, in the county of Suffolk and State of Massachusetts, have invented an Improvement in Annunciator-Drops, of which the following description, in connection with the accompanying drawings, is a specification, like letters on the drawings representing like parts.

10 This invention has for its object to construct an annunciator-drop.

In accordance with this invention, two bent arms or pieces are attached one to each end of a core, upon which a coil is wound, or may be formed integral with it, the said bent arms extending toward each other and forming the pole-pieces of the electro-magnetic device. The armature is attached to a flat spring secured to a post or frame, to which post or 20 frame the said electro-magnetic device is also attached. The target or disk is pivoted to the said post or frame, it having on its rear side a projection which engages, when lifted, the retracted armature, but which is released 25 when the armature is attracted.

Figure 1 shows in front elevation the annunciator-drop embodying this invention, the target or disk being shown in dotted lines; and Fig. 2, a top view of the annunciator-drop 30 shown in Fig. 1.

The core *a* has a coil, *a'*, wound thereon. Two metallic pieces, *b* *b'*, bent at substantially right angles, are attached one to each end of the core *a*, said pieces being so positioned that the outer or free ends thereof extend toward each other, but not sufficiently so as to meet. Two flat-surfaced pole-pieces, *c* *c'*, are thus formed.

The device is attached to a post or frame, *d*, preferably by the same fastening employed to attach one of the bent pieces to the core. The armature *e* is attached to a flat spring, *e'*, secured to the said post or frame *d*, said armature being rectangular in shape and adapted to make contact with both the pole-pieces *c* *c'*. The target or disk *f* is pivoted to the said post or frame *d*, it having on its rear side a projection, *f'*. When the armature *e* is retracted and the target or disk lifted, the projection *f'* bears upon the upper side of the 40 said armature; but when the armature is attracted the said target or disk will be released and fall by gravity in the usual manner.

The device herein described is very cheap to manufacture, is durable and powerful, it 55 presenting large-surfaced pole-pieces for the armature.

I claim—

The annunciator-drop herein described, comprising the core *a*, coil *a'*, metallic pieces 60 *b* *b'*, bent to present large flat-surfaced pole-pieces *c* *c'*, the armature *e*, attached to a spring, *e'*, the target or disk *f*, pivoted to move in a plane parallel with the flat-surfaced pole-pieces, and the support *d*, substantially as described.

In testimony whereof I have signed my name to this specification in the presence of two subscribing witnesses.

JOHN M. STUART.
